DRILL STEEL RETAINER

William A. Smith, Jr., North Arlington, N. J., and Herman J. Schorle, Astoria, Long Island, N. Y., assignors to Worthington Pump and Machinery Corporation, New York, N. Y., a corporation of Virginia

Application March 16, 1934, Serial No. 715,884

2 Claims. (Cl. 12—32)

This invention relates to rock drills or analogous percussive tools and more particularly to drill steel retainers therefor.

An object of the invention is to provide a drill steel retainer which will prevent ejection of the drill steel from the front head of the drill during operation, one which is rugged in construction and which may be quickly and easily moved into or out of drill steel retaining position. 10 With these and other objects in view as may appear from the accompanying specification, the invention consists of various features of construction and combination of parts, which will be first described in connection with the accompanying drawing, showing drill steel retainers of the preferred form, and the features forming the invention will be specifically pointed out in the claims.

In the drawing:

20 Fig. 1 is a side elevation partly in section of the improved drill steel retainer.

Fig. 2 is a longitudinal section through the drill steel retainer taken on the line 2—2 of Fig. 1.

25 Fig. 3 is a cross section through the retainer taken on the line 3—3 of Fig. 1.

Referring more particularly to the drawing, the front head of any approved type of rock drill or percussive tool is shown at 1 which front head receives in its forward open end the collared drill steel 2. The drill steel 2 has the usual form of collar 3 formed thereon which cooperates with the drill steel retainer in preventing the drill steel from being ejected from the 35 drill during operation.

The front head 1 has a pair of trunnions 5 formed thereon and projecting laterally therefrom on which trunnions are swingably hung the retainer bolts 6. There are two of the retainer bolts 6 and they are of similar construction. Each of the retainer bolts 6 comprises a head 7 which is rockably mounted upon the trunnion 5 to permit swinging of the bolt and of the yoke-like retainer proper 8. The yoke-like retainer 8 is substantially U-shaped and has heads 9 formed on the front ends of its legs which heads receive the retainer bolts 6 therethrough, as clearly shown in Fig. 2 of the drawing. The retainer 8 has a retaining head 10 formed at its forward end which is open at one side and through which the drill steel extends as clearly shown in Figs. 1 and 3 of the drawing. The retaining head 10 is of such size as to prevent the passage of the collar 3 therethrough.

Shock-absorbing springs 11 are mounted about the retainer bolts 6, are tensioned by nuts 12 and engage the outer sides of the heads 9 so as to provide yieldable shock-absorbing connection between the drill steel retainer and the drill proper through the medium of the retainer bolts 6. 5

The retainer bolts 6 have steadyng or supporting rod extensions 14 formed thereon which project outwardly from the nuts 12 and extend through suitable ears 15 formed on the retainer 10 8 adjacent to the retaining head 10. The rods 14 are slidable in the ears 15 and they serve to steady and support the retainer 8.

The trunnions 5 have flattened surfaces 16 and 17 formed thereon at acute angles to each other 15 which flat surfaces are engaged by the latch or locking plunger 18 to hold the retainer either in steel retaining position or out of steel retaining position. The spring 19 engages the plunger 18 for urging it in locking position. 20

In the drill steel retainer illustrated in the drawing and just described, the springs 11 act only as shock absorbers and it is not necessary to overcome the tension of these springs to move the retainer 8 out of steel retaining position; therefore, the retainer may be easily moved from one position to the other and it is retained in such position by means of the retainer-bolt carried latches 18 while it is held steady in position by the support or steadyng rod extensions 14. 25 30

It will be understood that the invention is not to be limited to the specific construction or arrangement of parts shown but that they may be widely modified within the invention defined by 35 the claims.

What is claimed is:

1. In a percussive tool, the combination with a front head adapted to receive the collared shank of a drill steel and having laterally extending trunnions thereon, retainer bolts swingably carried by said trunnions, a substantially U-shaped retainer including leg portions and a retainer head and having laterally extending eyes at the ends of its leg portions, said eyes 45 slidably engaging upon said retainer bolts, nuts threaded on said bolts, springs between said nuts and said eyes, ears formed upon the retainer head of said substantially U-shaped retainer and projecting laterally therefrom, and extensions 50 formed upon said swingable bolts projecting outwardly from said nuts and extending slidably through said ears.

2. In a percussive tool, the combination with a front head adapted to receive the collared shank 55

of a drill steel and having laterally extending trunnions thereon, retainer bolts swingably carried by said trunnions, a substantially U-shaped retainer including leg portions and a retaining head for engagement with a drill steel, said retainer having laterally extending eyes at the ends of its leg portions which slidably engage upon said retainer bolts, nuts threaded on said bolts, springs between said nuts and eyes, laterally extending ears formed upon said retaining head and projecting laterally therefrom, exten-

sions formed upon the retainer bolts and extending outwardly from said nuts, said extensions extending slidably through said ears, said trunnions each having angularly disposed flat surfaces thereon, and spring-pressed locking plungers carried by said bolts for engagement with one of said flat surfaces at a time to hold said retainers in adjusted positions. 5
